(**) Term: **14 Years**

(57) **CLAIM**

The ornamental design for an operator's seat for construction machinery, as shown and described.

DESCRIPTION

(21) Appl. No.: **29/149,740**

FIG. 1 is a perspective view of an operator's seat for construction machinery showing our new design;

(22) Filed: **Oct. 18, 2001**

FIG. 2 is a front view thereof;

(30) **Foreign Application Priority Data**

FIG. 3 is a rear view thereof;

Apr. 19, 2001 (JP) 2001-011328

FIG. 4 is a left side view thereof;

(51) LOC (7) Cl. **15-03**

FIG. 5 is a right side view thereof;

(52) U.S. Cl. **D15/28**

FIG. 6 is a top plan view thereof; and,

(58) Field of Search **D15/22-26, 28, D15/30; D6/356; 180/326, 332-334**

FIG. 7 is a bottom plan view thereof.
